ATION OF CALIFORNIA.

CROWN-BLOCK APPARATUS.

Application filed December 31, 1923. Serial No. 683,798.

This invention relates to oil well apparatus and particularly to the cables and cable sheaves which are carried at the crown block of the derrick. The sheaves at the crown block usually operate to support a traveling block with a number of sheaves, and may also include special sheaves to be used with the sand line, and for operating standard tools. With the usual arrangement 10 of sheaves, the diameter of the sheaves is considerably limited, from which it follows that the cable, in passing onto the sheaves, is bent to a relatively small radius; this is destructive to the cables and is objectionable. 15 The general object of this invention is to provide a crown block apparatus having a simple construction enabling the diameter of the sheaves to be made relatively large. A further object of the invention is to 20 provide a simple and compact crown block construction which will facilitate the use of the cable in the manner suggested, and which will also enable the sand line sheave and crown sheave to be properly aligned with 25 respect to the center line of the well.

Further objects of the invention will appear hereinafter.

The invention consists in the novel features and combination of parts to be described hereinafter, all of which contribute 30 to produce an efficient crown block apparatus.

A preferred embodiment of the invention is described in the following specification, 35 while the broad scope of the invention is pointed out in the appended claims.

In the drawings:

Figure 1 is a plan view of a crown block embodying my invention;

40 Figure 2 is an elevation of the crown block shown in Figure 1;

Figure 3 is a vertical section taken about on the line 3—3 of Figure 2, but showing the supporting shaft and sheaves broken away; 45 this view particularly illustrates the means for shifting the shaft when the upper side of the same becomes worn;

Figure 4 is a plan of a crown block showing a modified embodiment of the invention, 50 that is, with a slightly altered organization of sheaves with respect to that shown in Figure 1.

Figure 5 is a vertical section through the crown block shown in Figure 1; this section is taken on the line 5—5 of Figure 1.

55 Figure 6 is a diagrammatic elevation illustrating the traveling block with its sheaves, and showing the manner in which they are supported from the crown block sheaves by the cable; and

60 Figure 7 is a side elevation of the sheaves and cables shown in Figure 6 and further illustrating the reeving, or passes of the cable.

In practicing our invention, we provide a 65 crown block having a plurality of substantially parallel sheaves, and a traveling block below the same having a plurality of sheaves; and we provide a cable suspending the traveling block from the crown block, which is 70 rove around the sheaves so that as the cable passes onto each sheave it bends in the same direction from the straight line in which the cable extends, or is moving.

We also provide a crown block of such 75 construction as will enable crown sheaves of relative large diameter to be employed.

We provide two alternative organizations or arrangements of the crown sheaves, both of which embody our invention. In one embodiment of the invention, the crown sheaves that support the traveling block are all on the same shaft, and in another embodiment, they are disposed on two shafts. In either case, the crown sheaves that support the 80 traveling block are disposed in two sets, and these sets are separated from each other so that a gap is formed between them.

The sand line and cable tool sheaves are 85 preferably mounted over and substantially 90 in alignment with the gap between the sets of sheaves. In the embodiment of the invention shown in Figures 1 and 2 in which the crown sheaves are supported on the same shaft, 1 represents the crown block of the 95 derrick, which includes a pillow block 2 supporting a plurality of sheaves indicated generally by the numeral 3 and disposed in two sets 3^a and 3^b.

This pillow block 2 may be composed of 100 three frames 4, 5 and 6, each frame being in the form of a vertical plate with a central opening 7 (see Fig. 2) and stiffened up by vertical side ribs 8; a flange 9 is provided

at the bottom which is bolted to a corresponding I-beam 10 disposed under each frame.

In the spaces between the I-beams 10, the 5 sheave sets 3^a and 3^b are disposed, the said sheaves being mounted upon a horizontal shaft 11 which is held fixed in integral brackets 12 formed on the flanges 9.

Above the pillow block 2, we support the 10 sand line sheave 13 and the regular crown sheave 14, said sheaves being supported in suitable brackets 15 resting on horizontal cross-beams 16, which are I-beams (see Fig. 2), and which operate as ties or tie-bars to 15 connect the upper ends of the frames 4, 5 and 6, to which they are bolted. The sheaves 13 and 14 are at right angles to the sheaves 3.

The intermediate one of the beams 10 is 20 preferably disposed slightly away from the middle axis of the construction as viewed in plan, so that the inner edges 17 and 18 of the sheaves 13 and 14 can be disposed opposite to each other and substantially in line 25 with the axis of the well; they are right over the gap 19 which is formed between the two sheave sets 3^a and 3^b.

Referring to Figure 3, the sheaves 3 are mounted on roller bearings 20. It will be 20 evident that the wear on the shaft 11 takes place principally on the upper side of the shaft. We provide means for taking care of this wear by shifting the shaft into a reversed position; in other words, we provide 35 means to enable the shaft to be held in a position turned on its axis through 180 degrees from its first position, so as to bring the under face of the shaft uppermost. In order to do this, and at the same time enable 40 the shaft to be held securely, we provide the brackets 12 with means for holding the shaft fixed in either of these two positions. This may be accomplished in any 45 suitable manner. As illustrated in Figure 2, we cut away the end face of the shaft at two diametrically opposite points so as to form a transverse shoulder 21 at an elevated point and a transverse shoulder 22 at a depressed or lower level. On the cap 50 23 of the adjacent bracket 12, we provide a transverse plate 24, the lower edge of which engages the shoulder 21 and locks the shaft against rotation. These two shoulders 21 and 22 are parallel with each other and 55 are located at an equal distance from the axis of the shaft. Hence, when the upper face 25 of the shaft (see Fig. 3) becomes worn, the cap should be loosened, and the shaft may then be rotated on its axis 60 through 180 degrees so as to bring the shoulder 22 uppermost, whereupon the cap 23 will be reseated with the locking plate 24 engaging the shoulder 22.

Instead of having all of the lower crown 65 sheaves on the same shaft, we may mount forth.

them on two shafts 26 and 27 (see Fig. 4). These shafts are parallel with each other and disposed slightly apart. The sheaves are, as before, disposed in two sets, each set being composed of three sheaves 28^a, 29^a, and 28^b, respectively. The sheaves 28^a are disposed between the sheaves 28^a and 28^b. In other words, the sheaves overlap each other in side elevation (see Fig. 7). In this instance the crown block 29 may include 75 a pillow block 30 built up of three frames like the frames 4, 5 and 6, and tied together above by I-beams 31 disposed parallel to each other and slightly apart so as to provide a space for mounting the sand line sheaves 32 and the regular crown sheave 33. In this case, the sheaves 32 and 33 are mounted in the same vertical plane and with their adjacent edges disposed over the gap 34 which is formed between the two 85 sets of lower crown sheaves.

With such an organization of sheaves, the cable 34^a is rove around the sheaves in the manner illustrated in Figures 6 and 7. In this view *a* indicates the straight run of the 90 cable which is attached to the draw works. This run of the cable passes up over the sheave 28^b which causes the cable to be bent toward the left as it passes onto the sheave. From the sheave 28^b the run *b* passes down 95 to one of the sheaves 35 in the traveling block 36 and in passing onto this sheave 35 the cable is also bent to the left. The straight run *c* of the cable passing up from the sheave 35 passes onto the next adjacent 100 crown sheave and passes around it by bending to the left, as before.

After passing over all of the sheaves in this way as illustrated in Figures 6 and 7, the last run *n* of the cable passes down to 105 the calf-wheel. For convenience in following the direction of reeving the loops or "falls" of the cable illustrated in Figure 6, the successive runs have been lettered—*a*, *b*, *c*, *d*, *e*, *f*, *g*, *h*, *k*, *l*, *m*, and *n*, with a 110 small arrow near each letter indicating the direction of pull in the cable, it being understood that the cable is being taken up by the drawworks.

It will be evident that with the organization of sheaves described above, there is ample clearance for the sheaves, which enables them to be made with relatively large 115 diameters.

For lubricating the bearings the shaft 120 11 is provided with suitable oil ports 37 closed at their outer ends by suitable plugs 38.

It is understood that the embodiment of the invention described herein is only one 125 of the many embodiments this invention may take and we do not wish to be limited in the practice of the invention nor in the claims to the particular embodiment set

What we claim is:—

1. In a crown block construction for oil well derricks, the combination of a pillow-block, a plurality of aligned sheaves carried by the pillow-block disposed so as to form a gap at about the central vertical axis of the crown block, and a pair of sheaves disposed in a plane substantially at right angles to the plane of the first named sheaves, and supported on the block above the first named sheaves with their inner side edges substantially over the said gap. 5
2. In a crown block construction for oil well derricks, the combination of a pillow-block, a plurality of sheaves rotatably supported in the pillow-block and disposed in sets, one of said sets being separated from the other, so as to leave a gap between the sets, and a pair of sheaves supported on the pillow block above the first named sheaves 10
- and disposed with their inner side edges over the said gap. 5
3. In a crown block construction for oil well derricks, the combination of a pillow-block, a plurality of sheaves rotatably supported in the pillow-block, said sheaves being disposed in two sets separated from each other so as to form a gap between the sets, and a pair of sheaves supported on the pillow-block above the first named sheaves 25 and mounted to rotate on axes substantially at right angles to the axes of the lower sheaves, said upper sheaves having their inner side edges disposed substantially in line with the said gap. 30

Signed at Torrance, California this 19th day of December 1923.
